UNITED STATES PATENT OFFICE.

JOHN CAMPBELL, OF NEW YORK, N. Y.

DESIGN FOR A HOOF-PAD.

SPECIFICATION forming part of Design No. 35,698, dated February 4, 1902.

Application filed October 17, 1901. Serial No. 79,050. Term of patent 14 years.

To all whom it may concern:

Be it known that I, JOHN CAMPBELL, a subject of the King of Great Britain, and a resident of the city of New York, borough of Manhattan, in the county and State of New York, have invented and produced a new and original Design for a Hoof-Pad, of which the following is a specification, reference being had to the accompanying drawings, forming part thereof, in which—

Figure 1 is a perspective view of the bottom of the pad, and Fig. 2 is a similar view of the top.

The design comprises the body A, having at its side edges forward of the heel B at the quarter the shoe-recesses C C, the inner walls of which recesses are formed by the outer surfaces of projections D. In the body at the

under side there is a depression or pneumatic chamber E, which narrows toward the front 20 of the pad, and from said chamber a channel e leads through the heel of the pad to the back edge.

Having thus described my invention, what I claim as new, and desire to secure by Letters 25 Patent, is—

The design for a hoof-pad, as herein shown and described.

In testimony whereof I have signed my name to this specification in the presence of 30 two subscribing witnesses.

JOHN CAMPBELL.

Witnesses:

W. IRVING TAYLOR,
WILLIAM E. PARREMORE.
